UNITED STATES PATENT OFFICE.

HERBERT G. MACKINNEY, OF NEWARK, NEW JERSEY.

ENVELOPE FOR MAILING PACKAGES.

SPECIFICATION forming part of Letters Patent No. 471,846, dated March 29, 1892.

Application filed June 1, 1891. Serial No. 394,723. (No model.)

To all whom it may concern:

Be it known that I, HERBERT G. MACKINNEY, a citizen of the United States, residing at Newark, State of New Jersey, have invented 5 certain new and useful Improvements in Envelopes for Mailing Packages; and I do hereby declare the following to be a full, clear, and exact description of the invention, such as will enable others skilled in the art to which

10 it appertains to make and use the same.

My invention relates to envelopes for mail matter; and its object is to provide a safe and convenient package for fragile articles, with a convenient flap for addressing the package, 15 canceling the stamp, and impressing the seal of the post-office thereon. I have also provided a fastening device which adapts it to be used as an unsealed envelope and which may be supplemented by sealing-wax, mucilage, 20 or other adhesive matter when it is desired to send the package as a sealed envelope.

Reference is had to the accompanying drawings, wherein the same parts are indicated by the same letters.

25 Figure 1 represents a perspective view of the device after being mailed. Fig. 2 represents a perspective view of the wrapper and the portion of the box glued thereon or otherwise attached thereto. Fig. 3 represents one 30 portion of the box, in this case the top, and the means of attaching the wrapper and eye thereto. Fig. 4 represents an enlarged perspective view of the other portion of the box, in this case the bottom.

35 A represents a blank of paper, linen, or other suitable material glued or otherwise fastened to the top B of a box of pasteboard, tin, wood, or any suitable material and of any convenient shape. It is immaterial whether 40 the said blank of paper be attached to the top B or to the bottom or body B of the box. The blank A has wings or flaps a, adapted to turn up over the ends of the box, while its outer end is cut into a long tongue a', which 45 is bent back upon itself to give a double thickness and increased strength. The double thickness is pressed or glued together. Between the two thicknesses a reinforce of linen a² or other similar material may be glued or

otherwise secured. The eye C may be attached to the blank A or box B, or to both, in any convenient way.

For the paper-fastener D, I have shown a perforated paper disk d', Fig. 2, glued to the tongue a', and through this disk the prongs 55 of the paper-fastener may be inserted; but any other means of attaching the said paper-fastener to the said tongue may be adopted, or it may be simply pushed through the paper at the spot desired.

60 E (shown in dotted lines in Fig. 1) represents a wafer which may be applied to seal the package, should that be desired. Its presence will warn the postmaster and the public that the package is sealed. Any other mode 65 of sealing, however, may be adopted.

The operation of my device is as follows: The article having been packed in the box and the cover put on as usual, the flaps a are turned up over the ends of the box and the 70 blank A is wrapped once around the box, when the prongs of the paper-fastener D are pushed through the eyelet C and then bent over, securely engaging the wrapper. The package may be sealed before or after bending over the said prongs. It will be seen that 75 it will be impossible by any ordinary accident to detach the box from its wrapper. Moreover, the strong mailing tag or tongue will enable the address to be conveniently 80 written, the stamp applied, and the package to be conveniently postmarked, the stamp canceled, &c.

Having thus described my invention, what I claim, and desire to secure by Letters Patent of the United States, is—

1. In an envelope for mailing packages, the combination of a box made in a plurality of superimposable sections, a wrapper A, attached to one of those sections and having 90 flaps a and tongue a', with a fastening device attached, respectively, to the base of said tongue and to the said section of said box, substantially as described.

2. In an envelope for mailing packages, the 95 combination, with a box composed of two superimposable sections, of the wrapper A, attached to one of said sections and having the

the flaps a , double tongue a' , and fastening devices C and D, substantially as described.

3. In an envelope for mailing packages, the combination, with a rectangular box composed of two superimposable sections, a top, and a bottom or body of the box, of the wrapper A, attached to one of said sections and having the flaps a , doubled tongue a' , rein-

force a^2 , and fastening devices C and D, substantially as described.

In testimony whereof I affix my signature in presence of two witnesses.

HERBERT G. MACKINNEY.
